UNITED STATES PATENT OFFICE.

WARREN F. FRASER, OF DORCHESTER, MASSACHUSETTS, ASSIGNOR TO FRASER MACHINE & MANUFACTURING CO., A CORPORATION OF MASSACHUSETTS.

DEVICE FOR FEEDING LACING-HOOKS AND THE LIKE.

No. 901,434.

Specification of Letters Patent.

Patented Oct. 20, 1908.

Application filed January 11, 1908. Serial No. 410,408.

To all whom it may concern:

Be it known that I, WARREN F. FRASER, a subject of King Edward VII, residing at Dorchester, in the county of Suffolk and State of Massachusetts, have invented new and useful Improvements in Devices for Feeding Lacing-Hooks and the Like, of which the following is a specification.

This invention relates to a device for feeding lacing hooks or the like, the object of the invention being to provide a simple and reliable mechanism for feeding lacing hooks from a column of lacing hooks on a raceway to a carrier, said carrier holding the lacing hook in position while the same is being riveted in the upper of a boot or shoe.

The object of the invention is further to provide a device in which the mechanism is reduced to a small number of parts and which is capable of feeding a lacing hook from the foot of a vertical raceway and from a horizontal position onto a carrier and to place the same on said carrier in a vertical position.

The object of the invention is further to feed the lacing hook from the raceway to the carrier with one moving piece, which moving piece shall not only feed the lacing hook from a horizontal position from the raceway to a carrier and place the same on said carrier in a vertical position, but shall also close the vertical raceway at the foot thereof to prevent any of the lacing hooks in the column of lacing hooks on said raceway from moving downwardly while said lacing hook is being fed from the raceway to the carrier and while the moving piece is returning in readiness to feed another lacing hook from the raceway to the carrier.

The invention consists in a device of the character described in the following specification and particularly as pointed out in the claims thereof.

Referring to the drawings: Figure 1 is a side elevation, partly in section, of a portion of the frame of a lacing hook setting machine, with my improved device for feeding lacing hooks attached thereto together with a lacing hook carrier and anvil, the device being shown with the parts in the positions assumed thereby when the lacing hook has just been fed onto the carrier. Fig. 2 is a view similar to Fig. 1, showing the parts in the relative positions assumed thereby when the feeding plunger is just about to feed a lacing

hook from the raceway toward the lacing hook carrier. Fig. 3 is a perspective view of the plunger. Fig. 4 is a perspective view of the tubular guideway, with a portion of the raceway attached thereto. Fig. 5 is a detail sectional elevation taken on line 5—5 of Fig. 2, looking toward the right in said figure. Fig. 6 is a front elevation of the raceway, tubular guideway and plunger. Fig. 7 is a transverse sectional elevation taken on line 7—7 of Fig. 1, looking toward the right in said figure and showing a lacing hook in position within the helical groove of the tubular guideway.

Like numerals refer to like parts throughout the several views of the drawings.

In the drawings, 10 is the frame of a lacing hook setting machine of any suitable form or design. 11 is a tubular guideway fastened to a hub 12 on said frame by a set-screw 13. 75 The tubular guideway 11 is provided with a helical groove 14 which is adapted to receive a lacing hook and guide the same from a horizontal position at the foot of the raceway 15 to a vertical position upon the lacing hook 80 carrier 16. The tubular guideway 11 has a collar 17 fast thereto and flattened off at one side, and to this collar are fastened the several portions of the raceway, including the guide-piece 18, the cap-piece 19 and the foot-piece 20.

An anvil 21 is located above the carrier 16 and in alignment with the shank of the lacing hook when the same is placed thereon in readiness to be riveted in the upper of a boot 90 or shoe. The groove 14 has its opposite edges formed to project into the space between the head and flange of a lacing hook 22 in said groove upon opposite sides, respectively, of the neck of said lacing hook. The 95 lacing hook is moved from the bottom of the raceway along the groove 14 to the position illustrated in Fig. 1 upon the carrier 16 by a helical shaped finger 23 which projects into the groove 14 and is preferably V-shaped at 100 its forward end in order that the same may fit into the laterally curved portion of the neck of the lacing hook while pushing the same from the foot of the raceway onto the carrier. The finger 23 projects from a 105 plunger 24 which extends through the tubular guideway 11, said finger being of sufficient length to contact with the lacing hook which stands upon the carrier and to project rearwardly therefrom beneath the lowermost 110

lacing hook on the raceway, as seen in Fig. 1, thus preventing said lowermost lacing hook from descending into the groove 14 until the plunger has moved backwardly and its forward end is at the right of the lowermost lacing hook in the raceway (Fig. 2).

A reciprocatory movement is imparted to the plunger 24 by a lever 25 to which a rocking movement is imparted by suitable mechanism, not shown in the drawings. Said lever 25 is forked to receive two lateral pins 26, which project thereinto, these lateral pins being rigidly fastened to or integral with a collar 27 in which collar the plunger 24 is free to rotate. A nut 28 holds the collar upon the plunger 24 and against a shoulder 29 formed upon the plunger 24, but it will be understood that said nut does not clamp the collar 27 against the shoulder 29, but simply holds said collar upon the plunger and free for said plunger to rotate within said collar as the same is being moved forwardly and backwardly by the lever 25.

The general operation of the device hereinbefore specifically described is as follows: The lacing hooks are fed down the raceway, which is preferably vertical, from a hopper or any other suitable separating device until they stand in column upon said raceway, with the lowermost lacing hook resting against the helical guide-finger 23. Said guide-finger is moved backwardly to the position shown in Fig. 2, whereupon the lowermost lacing hook in the raceway drops into the groove 14 and the plunger 24 is then moved forwardly or toward the left from the position illustrated in Fig. 2 to that illustrated in Fig. 1, carrying with it, by reason of the finger 23 pushing against the neck of said lacing hook, the lacing hook 22 from a horizontal to a vertical position and pushing the same onto the carrier 16. The carrier then ascends and drives the shank of the lacing hook through the upper of the boot or shoe and clenches the same therein in a manner well known to those skilled in the art. During this clenching operation the plunger is moved toward the right from the position illustrated in Fig. 1 to that illustrated in Fig. 2, and thus allows a lacing hook, 22', to drop from the column of lacing hooks into the groove 14, and said lacing hook is then fed onto the carrier, as hereinbefore described, preparatory to being set in the leather of the upper.

Having thus described my invention, what I claim and desire by Letters Patent to secure is:

1. A device for feeding lacing hooks or the like comprising a raceway, a carrier adapted to receive a lacing hook, a guideway extending from the foot of said raceway toward said carrier, said guideway provided with a helical groove adapted to guide a lacing hook, and means to move the lacing hook along said

helical groove from the foot of said raceway onto said carrier.

2. A device for feeding lacing hooks or the like comprising a vertical raceway, a carrier adapted to receive a lacing hook, a guideway extending from the foot of said raceway to said carrier, said guideway provided with a helical groove adapted to guide a lacing hook and rock the same from a horizontal to a vertical position, and means to move a lacing hook along said helical groove from the foot of said raceway onto said carrier.

3. A device for feeding lacing hooks or the like comprising a raceway, a carrier adapted to receive a lacing hook, a guideway extending from the foot of said raceway toward said carrier, said guideway provided with a helical groove adapted to guide a lacing hook, a finger projecting into said helical groove adapted to engage said lacing hook at the foot of said raceway, and means to move said finger longitudinally of said groove, whereby said lacing hook may be moved along said helical groove from the foot of said raceway onto said carrier.

4. A device for feeding lacing hooks or the like comprising a raceway, a carrier adapted to receive a lacing hook, a tubular guideway extending from the foot of said raceway toward said carrier, said guideway provided with a helical groove adapted to guide a lacing hook, a plunger within said tubular guideway, a finger projecting from said plunger into said groove adapted to engage a lacing hook at the foot of said raceway, and means to impart a reciprocatory movement to said plunger.

5. A device for feeding lacing hooks or the like comprising a raceway, a carrier adapted to receive a lacing hook, a tubular guideway extending from the foot of said raceway toward said carrier, said guideway provided with a helical groove adapted to guide a lacing hook, a plunger within said tubular guideway, a helical shaped finger projecting from said plunger into said groove adapted to engage said lacing hook at the foot of said raceway, and means to impart a reciprocatory movement to said plunger, whereby said lacing hook may be moved along said helical groove from the foot of said raceway onto said carrier.

6. A device for feeding lacing hooks or the like comprising a raceway, a carrier adapted to receive a lacing hook, a tubular guideway extending from the foot of said raceway toward said carrier, said guideway provided with a helical groove adapted to guide a lacing hook, a plunger within said tubular guideway, a helical shaped finger projecting from said plunger into said groove adapted to engage said lacing hook at the foot of said raceway, and means to impart a reciprocatory movement to said plunger, whereby said lacing hook may be moved along said

- helical groove from the foot of said raceway onto said carrier, said finger being of sufficient length to extend across the foot of said raceway when the forward end of said finger 5 is in contact with a lacing hook on said carrier.
7. A device for feeding lacing hooks or the like, comprising a raceway, a carrier adapted to receive a lacing hook, a tubular guideway 10 extending from the foot of said raceway toward said carrier, said guideway provided with a helical groove adapted to guide a lacing hook, a plunger within said tubular guideway, a finger projecting from said plunger into said groove, a collar in which said plunger is adapted to rock, and a lever connected to said collar, whereby said plunger 15 is adapted to be reciprocated and rocked simultaneously.
8. In a device for feeding lacing hooks or the like, a tubular guideway provided with a helical groove adapted to guide a lacing hook, a plunger within said tubular guideway, a finger projecting from said plunger into said groove adapted to engage a lacing hook in 20 said groove, and means to impart a reciprocatory movement to said plunger.
- 25

9. In a device for feeding lacing hooks and the like, a tubular guideway provided with a helical groove adapted to guide a lacing hook, a plunger within said tubular guideway, a helical shaped finger projecting from said plunger into said groove adapted to engage and formed at its free end to enter the laterally curved portion of a lacing hook in 30 said groove, and means to impart a reciprocatory movement to said plunger.

10. In a device for feeding lacing hooks or the like a tubular guideway provided with a helical groove, the edges of said groove being 40 adapted to project into the space between the head and flange of a lacing hook in said groove and upon opposite sides, respectively, of the neck thereof and to guide said lacing hook from a horizontal to a vertical 45 position as the same is moved longitudinally of said guideway.

In testimony whereof I have hereunto set my hand in presence of two subscribing witnesses.

WARREN F. FRASER.
